UNITED STATES PATENT OFFICE.

JOSEPH SCHNEIBLE, OF NEW YORK, N. Y.

MANUFACTURE OF FERMENTED LIQUORS.

SPECIFICATION forming part of Letters Patent No. 734,756, dated July 28, 1903.

Application filed January 2, 1903. Serial No. 137,545. (No specimens.)

To all whom it may concern:

Be it known that I, JOSEPH SCHNEIBLE, a citizen of the United States, residing in the borough of Manhattan, city of New York, in the State of New York, have invented certain new and useful Improvements in the Manufacture of Fermented Liquors, of which the following is a specification.

It has been proposed heretofore to shorten the time required for the finishing of fermented liquors, to prevent deterioration of such liquors during treatment, and to reduce the cost of the treatment as well as the cellar-space required by cooling newly-fermented liquor, charging it with carbonic-acid gas, and finally resting the liquor so cooled and charged until coagulation of the albuminous matters is effected.

In the practice of the method referred to it was assumed that the carbonic-acid gas to be used might be derived from any convenient source, such as vessels in which fermentation of liquor was carried on, but that such gas should be practically pure carbonic-acid gas, provisions for the storage and washing of the gas derived from fermentation being contemplated as an adjunct to the operation. When practiced under favorable conditions, the former method gave results which were satisfactory, at least as compared with other methods; but it has been found that still better results can be attained, particularly with regard to the character of the finished product, while the range of conditions under which the method can be advantageously employed is widely extended by modifying or varying the former method in some particulars which are now found to be of vital importance. The change of the greatest importance and that upon which the new method depends for the attainment of the best results is in the character of the gas with which the liquor is charged, particularly in its relation to the condition of the liquor at the time of charging. Heretofore it was thought desirable that the gas used should be as nearly pure carbonic-acid gas as it was practicable to obtain, and when such gas was derived from fermentation it was supposed that it could be, and as a matter of practice it was, held in storage for an indefinite time after its generation and was

usually subjected to purification. In these ways the character of the gas used for charging the liquor became, as it has now been discovered, substantially different from that of the mixture of gas and volatile matter given off by the fermenting liquor. The volatile matters which are carried by the carbonic-acid gas at the time of its generation and are now found to be of primary importance lost their effectiveness during storage and were removed by the purifying processes. Under the present improved method the gases of fermentation and the volatile matters carried thereby are used for the charging of the fermented liquor as nearly as possible in the condition in which they are given off by fermenting liquor, and it has been found that under ordinary conditions a storage of the gaseous and volatile products of fermentation for a longer period than about two days is undesirable by reason of the change in the character thereof which takes place at about that period. Other variations in the former method, either permissive or desirable, will be referred to hereinafter or will be apparent upon comparison of this new method, as herein described, with the former methods.

In the practice of the improved method, which may be carried on in any suitable apparatus, the liquor is fermented in the usual manner or preferably at a somewhat higher temperature than usual and is separated from the yeast. In the ordinary methods of brewing the liquor is sometimes allowed to remain with the yeast while being cooled until coagulation of albuminous matters in the liquor takes place to some extent; but in the practice of the improved method it is desirable that the liquor shall be separated from the yeast before such coagulation of the albuminous matters takes place and while they still remain in solution or semisolution in the liquor. While the liquor is in this condition it is charged with the fresh gaseous and volatile products of fermentation as nearly as possible in the condition in which they are given off by fermenting liquor. As already indicated, it is found that when such gaseous and volatile products of fermentation are stored for a period of more than about two days under usual conditions such a change takes place

in such gaseous and volatile matters as to seriously affect the reaction of such gaseous and volatile matters on the albuminous or other matters which are contained in the beer to be treated. In order that such desired reaction may take place and that the results which follow therefrom may be attained, it is found necessary under usual conditions to use such gaseous and volatile products of fermentation within about two days after they are given off. In fact, the best results are secured when such gaseous and volatile products are used immediately after being given off. The result which is thus chiefly aimed at is such a change in the physical condition of the undesirable albuminoids, commonly called "proteids," in the beer as to permit the removal of such proteids in a greater quantity and more thorough than has been possible heretofore, even during long-continued storage. The coagulation of such proteids when thus acted upon takes place quickly, and their precipitation proceeds with correspondent rapidity. The products of fermentation might be those derived from the previous fermentation of the liquor which is under treatment, provided the time which elapses between the fermentation and the charging of the liquor is not too long. It is preferable, however, to collect these products from liquor which is being fermented at the time. In every case convenience will dictate the source from which the products of fermentation used in charging the liquor are to be derived, subject to the provision that they shall be in substantially the same condition or substantially as fresh as when given off. The temperature to which the liquor is reduced at the time of charging or subsequent thereto should be such as to promote the absorption and retention of the volatile matters by the liquor and the action of such matters upon the liquor. Under ordinary conditions this temperature is found to be about that at which the liquor has its greatest density; but it may vary somewhat therefrom under different conditions. After the liquor has been treated with the products of fermentation it is allowed to rest while coagulation and separation of the albuminous matters and clarification of the liquor take place. The use of chips for clarification and pressure on the liquor while resting, which are essentials of the ordinary methods of manufacturing fermented liquors, are unnecessary and superfluous in the practice of the improved method.

For the purpose of further explanation of a satisfactory manner of practicing the invention such apparatus as may be employed is represented in outline or diagrammatically in the accompanying drawing. The fermentation of the beer may be carried on in tub *a*, as fully described in Letters Patent No. 700,833, dated May 27, 1902, the fermentation being allowed to progress until the maximum temperature is attained. From the tub *a* the beer may then be transferred to another tub, as *b*, wherein the fermentation is com-

pleted and the yeast for further use is separated. After the separation of the yeast, which ordinarily takes place in about two days, the beer is conducted to the finishing-cask *c*, receiving on its way a quantity of fresh gaseous and volatile products of fermentation. These products of fermentation may be collected directly from the tanks *a* and introduced into the beer by any suitable means—such, for example, as a jet-pump, (indicated at *d*), as disclosed in Letters Patent No. 438,086, dated April 23, 1895. As the beer which leaves the cask *b* is at a comparatively high temperature, it is desirable to cool it on its way to the finishing-cask, and for this purpose an ordinary cooler *e*, such as is well known in the art, is provided. Whether the apparatus be arranged as represented in the drawing or in any other suitable manner it will be observed that the beer itself is treated while the albuminous matters are in a state of solution or semisolution therein and that the beer in that condition is treated with the gaseous and volatile products of fermentation, while they also are substantially in the condition in which they are given off by fermenting liquor.

I claim as my invention—

1. The improvement in the manufacture of fermented liquors which consists in fermenting the liquor, separating the fermented liquor from the yeast, charging the fermented liquor with fresh gaseous and volatile matters given off by fermenting liquor while such gaseous and volatile matters are substantially in the condition in which they are given off by fermenting liquor, and resting the charged liquor while coagulation and separation of the albuminous matters take place. 95

2. The improvement in the manufacture of fermented liquors, which consists in fermenting the liquor, separating the fermented liquor from the yeast while the albuminous matters are in solution or semisolution therein, charging the fermented liquor with fresh gaseous and volatile matters given off by fermenting liquor while such gaseous and volatile matters are substantially in the condition in which they are given off by fermenting liquor, and resting the charged liquor while coagulation and separation of the albuminous matters take place. 100

3. The improvement in the manufacture of fermented liquors, which consists in fermenting the liquor, separating the fermented liquor from the yeast, charging the fermented liquor with the fresh gaseous and volatile matters given off by fermenting liquor while such gaseous and volatile matters are substantially in the condition in which they are given off by fermenting liquor, and reducing the temperature of the liquor to promote the absorption and retention of the gaseous and volatile matters by the liquor and the action of such matters on the liquor, and resting the charged liquor while coagulation and separation of the albuminous matters take place. 120 125 130

4. The improvement in the manufacture of fermented liquors, which consists in fermenting the liquor, separating the fermented liquor from the yeast while the albuminous matters are in solution or semisolution therein, and charging the fermented liquor with the fresh gaseous and volatile matters given off by fermenting liquor while such gaseous and volatile matters are substantially in the con-

dition in which they are given off by fermenting liquor.

This specification signed and witnessed this 4th day of December, A. D. 1902.

JOSEPH SCHNEIBLE.
